(57) CLAIM

The ornamental design for an armchair, as shown and described.

DESCRIPTION

FIG. 1 is a perspective view of an armchair in accordance with one preferred embodiment of this invention; FIG. 2 is a front view of the armchair, as shown in FIG. 1; FIG. 3 is a side view of the armchair as shown in FIG. 1; FIG. 4 is a back view of the armchair as shown in FIG. 1; and,

FIG. 5 is a top view of the armchair as shown in FIG. 1. The fragmented cross-hatching shown on the seat and backrest is understood to represent mesh and would be continuous throughout the circumscribed areas.
